UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL CONNECTER DEVICE.

Application filed February 23, 1922. Serial No. 538,715.

My invention relates to electrical connector devices, and more particularly to electrical connector devices suitable for use where it is desired to connect a number of small lights, such as are used for Christmas tree ornaments, or the like, in parallel between two main feed wires.

One of the objects of my invention is to provide such a connector which will permit of ready connection and disconnection of the individual lamp sockets and branch wires.

A further object of my invention is to provide such a connector device which will be durable and efficient in use, simple in construction and cheap to manufacture.

Further objects will appear from the detailed description to follow, and from the appended claims.

In the drawing in which an embodiment of my invention is shown—

Figure 1 is a side elevation of an electrical connector device;

Fig. 2 is an axial section on the line 2—2 of Fig. 1;

Fig. 3 is a section on the line 3—3 of Fig. 2;

Fig. 4 is a view looking down on Fig. 2 with the upper cap removed;

Fig. 5 is a view looking up at Fig. 2 with the lower cap removed;

Fig. 6 is a view of the under side of the upper cap;

Fig. 7 is a view of the upper side of the lower cap;

Fig. 8 is a perspective view showing one of the blade-engaging contacts, and

Fig. 9 is a side view of one of the contact blades.

Referring now to the drawings in detail, the construction shown therein comprises an electrical connector device secured to the main feed wires 10, and serving to connect the branch wires 11 with the main feed wires 10. A number of these connectors 12 may be strung along the main feed wires 10 to connect any desired number of lamps in parallel between the feed wires 10.

The cap member 13 of the connector 12 is provided with a pair of contact blades 14, which can be plugged in to engage with contact members 15 which are connected with the feed wires 10 respectively. The blades 14 are mounted on an insulating cap 16. This cap is provided with an axial opening 17

through which the lamp wires 11 pass for connection with the blades 14.

In order to relieve the strain on the connection between the wire 11 and the contact blade 14, the wire 11 is led around the edge of the contact blade 14 and secured to that side of the contact blade which is farthest from the axial opening 17, as by soldering or in any suitable manner as indicated at 18. The bending of the wire around the edge of the contact blade prevents a direct pull being exerted on the wiring connection and thus relieves the strain.

The blade-engaging contacts 15 are mounted in suitable recesses in an insulating base 19. An insulating cap 20 is provided secured to the insulating base 19, this cap extending across the recesses in which the blade-engaging contacts 15 are located, and serving to house them. The cap 20 may be secured to the base 19 by means of a screw 21 extending through registering openings in the base and cap and threaded into the nut 22 embedded in the cap 20.

As shown in Fig. 4, the insulating base 19 is provided with grooves 23, leading from one side to the other of the base, and past the blade-engaging contacts 15, these grooves 23 affording a passage for the main feed wires 10 which lie between the base 19 and cap 20.

Each blade-engaging contact 15, as shown in Fig. 8, comprises a U-shaped stamping, having one end provided at 24 with means to facilitate the securing thereto of the feed wires 10, and having its other free end 25 extending into a recess 26 in the cap 20 which affords clearance for the movement of this free end of the contact. The feed wire 10 is secured to the blade-engaging contact 15 by baring a portion of the wire and placing it between the lugs 27 and 28 formed at one end of the stamping.

In order to facilitate the withdrawal of the cap 13, the cap and base 19 may be provided with finger notches 29 and 30 respectively, whereby the parts may be readily grasped, one in one hand and the other in the other, to pull them apart.

In wiring the device, the cap member 13 is withdrawn, the cap 20 is disconnected from the body or base 19 by unscrewing the screw 21, the feed wires 10 are bared at the proper points and the bared portions placed

in proper position with respect to the lugs 27 and 28, the wires 10 are placed in the grooves 23 provided for them, and the cap 20 is placed in position and secured by means 5 of the screw 21.

Any number of these connectors may be applied to the feed wires at any desired point along the line, each one of these connectors affording an outlet for a small electric lamp which may be connected to the wires 11.

Having thus described my invention, what I claim as new and desire to secure by Letters Patent of the United States is:

15. 1. An electrical outlet comprising a housing and a closure therefor, oppositely disposed grooves therein for the reception of a duplex electrical conductor, oppositely disposed recesses in said housing extending therethrough on either side of the axis of 20 said grooves, plug contacts seated within said recesses, and adapted to receive corresponding plugs through the outer ends of said recesses, and means carried by the inner 25 ends of said plug contacts to engage the two wires respectively of said conductor, said wires being diverged within the housing and disposed on either side of the central axis, said housing and closure having a longitudinal 30 hole extending therethrough for the reception of a common fastening means.

2. An electrical outlet comprising a housing and a closure therefor, oppositely disposed transverse grooves therein for the reception of a duplex electrical conductor, oppositely disposed recesses in said housing on either side of said grooves and extending longitudinally through said housing, plug contacts seated within said recesses and 35 adapted to receive corresponding plugs through the outer ends of said recesses, and means carried by the inner ends of said plug contacts to engage the two wires respectively of said conductor, said wires being diverged within the housing and disposed on either side of the central axis, said housing and closure having a longitudinal hole 40 extending therethrough for the reception of a common fastening means, said closure 45 adapted to engage said plug contacts to maintain the same within said housing.

3. An electrical outlet comprising a housing and a closure therefor, oppositely dis-

posed transverse grooves therein for the reception of a duplex electrical conductor, oppositely disposed recesses in said housing on either side of said grooves and extending longitudinally through said housing, contacts seated within said recesses and adapted to receive corresponding plugs through the outer ends of said recesses, and means carried by the inner ends of said plug contacts to engage the two wires respectively of said conductor, said wires being diverged within the housing and disposed on either side of the central axis, said housing and closure having a longitudinal hole extending therethrough for the reception of a common fastening means, and said closure adapted to maintain said plug contacts within said 65 housing.

4. An electrical outlet comprising a housing and a closure therefor, oppositely disposed grooves therein for the reception of a duplex electrical conductor, oppositely disposed recesses in said housing extending therethrough on either side of the axis of said grooves, plug contacts seated within said recesses, and adapted to receive corresponding plugs through the outer ends of said recesses, and means carried by the inner ends of said plug contacts to engage the two wires respectively of said conductor, said wires being diverged within the housing and disposed on either side of the central axis, said housing and closure having a longitudinal hole extending therethrough for the reception of a common fastening means.

5. An electrical outlet comprising a housing and a closure therefor, oppositely disposed transverse grooves therein for the reception of a duplex electrical conductor, oppositely disposed recesses in said housing on either side of said grooves and extending longitudinally through said housing, contacts seated within said recesses and adapted to receive corresponding plugs through the outer ends of said recesses, and means carried by the inner ends of said plug contacts to engage the two wires respectively of said conductor, said wires being diverged within the housing and disposed on either side of the central axis, said housing and closure having a longitudinal hole extending therethrough for the reception of a common fastening means, and said closure adapted to maintain said plug contacts within said housing.

In witness whereof, I have hereunto subscribed my name.

REUBEN B. BENJAMIN.
